[57] CLAIM

The ornamental design for a golf towel holder, as shown and described.

DESCRIPTION

FIG. 1 is a front elevation view of a golf towel holder showing our new design;

FIG. 2 is another front elevation view thereof;

FIG. 3 is a side elevation view, the opposite side being a mirror image thereof;

FIG. 4 is a rear elevation view thereof;

FIG. 5 is a bottom plan view thereof; and,

FIG. 6 is a top plan view thereof.

The broken line showing of environment in FIG. 1 is for illustrative purposes only and forms no part of the claimed design.
